A. BUCKEL,
SACK HOLDER.
APPLICATION FILED MAY 3, 1919.

Patented Aug. 31, 1920.

Inventor.
A. Buckel.

By *Alfred J. Randolph Jr.* Attorney.

UNITED STATES PATENT OFFICE.

ALBERT BUCKEL, OF PERU, ILLINOIS.

SACK-HOLDER.

1,351,094.

Specification of Letters Patent. Patented Aug. 31, 1920.

Application filed May 3, 1919. Serial No. 294,362.

To all whom it may concern:

Be it known that I, ALBERT BUCKEL, a citizen of the United States, residing at Peru, in the county of La Salle and State of

Illinois, have invented certain new and useful Improvements in Sack-Holders; and I do hereby declare the following to be a full, clear, and exact description of the invention, such as will enable others skilled in the art

10 to which it appertains to make and use the same.

This invention relates to bag holders and the primary object of the invention is to provide an improved and simple means for

15 holding a bag or sack in an elevated and opened position, so as to facilitate the filling thereof.

Another object of the invention is to provide an improved sack holder of the above 20 character, which is durable and efficient in use, one that is simple and easy to manufacture, and one that can be placed upon the market at a reasonable cost.

With these and other objects in view, the 25 invention consists in the novel construction, arrangement and formation of parts, as will be hereinafter more specifically described, claimed and illustrated in the accompanying drawings, forming a part thereof, in which:

30 The figure is a perspective view of the improved bag holder.

Referring to the drawings in detail, the numeral 1 generally indicates the improved bag holder, which includes a bracket 2 35 formed from a piece of strap iron bent to form a substantially U-shaped member 3 including the upper bight portion 4 and the downwardly extending legs 5. The bight portion is provided with suitable

40 openings 6 for receiving bolts or other suitable fastening elements 7, whereby the legs may be secured to a wall or other support 8. The lower terminals of the legs have secured thereto a transversely extending bar 9, which

45 extends beyond the side edges of the legs and one end of this bar is bent at an angle of substantially forty-five degrees outwardly to form a supporting arm 10, which has the free end thereof curved outwardly as at 11.

50 The opposite terminal of the arm 9 is reduced and bent forwardly as at 12 and is provided with a hooked end 13, for receiving one terminal of a contractile coil spring 14, which has the opposite end thereof secured

55 to an outwardly extending plate 15 secured to the second supporting arm 16. The inner

end of the supporting arm 15 is hingedly secured as at 17 to the member 9 adjacent to the arm 10, and this arm is normally held away from the arm 10 by the contractile 60 coil spring 14. The plate 15 is provided with a plurality of openings 18 for receiving the inner terminal of the coil spring 14, so as to permit the tension thereof to be readily regulated. The free terminal of the 65 arm 16 is bent inwardly as at 19 and the bent terminals 11 and 19 of the arms 10 and 16 are provided with outwardly extending prongs 20 which are adapted to penetrate a bag or sack 21 to hold the same in open and 70 raised position. The arms 11 and 16 are curved, so as to facilitate the insertion of the same into the bag and to conform to the configuration thereof. The arms are also provided with retaining prongs 22 which are 75 arranged in spaced relation to the prongs 20 and form additional means for engaging the bag so as to hold the same open.

From the foregoing description, it can be seen that an improved bag holder is provided which will effectively hold the bag in elevated position and hold the same open, so as to facilitate the insertion of articles therein.

In use of the holder the arm 16 is swung 80 on its pivot against the tension of the coil spring 14 to a point relatively near the arm 10 and the curved portion thereof and the arm 10 is inserted into the bag and the prongs 20 and 21 are caught in the neck 90 thereof. The arm 16 is then released, which owing to the tension of the coil spring 14 will open the neck thereof and allow the articles to be readily inserted.

In practice, I have found that the form 95 of my invention illustrated in the accompanying drawings and referred to in the above description, as the preferred embodiment, is the most efficient and practical; yet realizing the conditions concurrent with the 100 adoption of my device will necessarily vary, I desire to state that various minor changes in details of construction, proportion and arrangement of parts may be resorted to, when in accord with the claim without sacrificing any of the advantages of my invention as set forth.

What I claim as new is:

A bag holder comprising a vertical base member arranged to be secured to a support, 110 a bag supporting member secured to the said base member, and having at one end

an outwardly extending arm at an angle thereto, a second arm pivotally secured to said supporting member and extending outwardly therefrom, the opposite end of said supporting member being bent forward and curved to form a retaining hook, a contractile coil spring secured to said hooked end and connected with the hinged arm, the free terminals of said arms being curved inwardly and prongs mounted upon the

arms some of them at the curved portions of the arms and others at points spaced therefrom.

In testimony whereof I affix my signature in presence of two witnesses.

ALBERT BUCKEL.

Witnesses:

WILLIAM HUETTEMANN, Jr.,
OSCAR W. HOBERG.
